Specification of Letters Patent.

Patented Feb. 10, 1914.

Application filed June 13, 1912. Serial No. 703,388.

To all whom it may concern:

Be it known that we, GEORGE S. WITHAM, Sr., and ISAAC J. WITHAM, citizens of the United States, residing at Hudson Falls, New York, have invented certain new and useful Improvements in Sheet-Delivery Apparatus, of which the following is a clear, full, and exact description.

This invention relates to a feeding machine which in the present instance is intended to be used to feed stock to a second machine which may form plates or other articles from the blanks fed to it. In the preferred embodiment of the invention, a web 10 of stock is divided or cut into blanks and these blanks are then delivered to the forming machine. In feeding machines of this general type it has been customary to provide the stock in the form of a supply roll 15 from which a web is drawn toward the forming machine. This web is cut in suitable lengths or blanks of stock which are then fed at the proper time, as for instance when the forming dies are presented to receive the blank. When the supply roll is exhausted it is necessary to set up a new supply roll of stock on the machine, and it has been heretofore necessary to thread the web of this new roll between the feeding rollers 20 or other devices of the feeding machine.

A principal object of the present invention is to provide a construction for the feeding machine which will enable two or more supplies of stock to be arranged ready for use, but only one of these supplies is actively in use at one time. An arrangement is provided, however, so that the web of the new supply of stock to be used may be partially drawn out or extended toward the forming machine. When the active stock supply, which may be in the form of a roll, becomes exhausted, the feeding of the web from the new supply or roll begins without stopping either the feeding mechanism or forming machine or causing any substantial delay.

The invention further consists in the general combination of parts and simplicity of details hereinafter described, all of which 50 contribute to produce an efficient feeding machine.

A preferred embodiment of our invention will be particularly described in the following specification, while the broad scope of

our invention will be pointed out in the appended claims.

In the drawings, Figure 1 is a side elevation of a feeding machine embodying our improvements, in their preferred form; Fig. 2 is a plan of the machine shown in Fig. 1; Fig. 3 is a section upon an enlarged scale taken on the line 3—3 of Fig. 2, and particularly illustrating the means for advancing the web of the fresh roll when the roll being used has become exhausted. This view also illustrates the operation of the knife which cuts the web into blanks; Fig. 4 is a vertical section on the line 4—4 of Fig. 2, and illustrating the arrangement of the delivery belts which pass or throw the blank 70 from the feeding machine into the dies of the forming machine; Fig. 5 is a section taken about on the line 5—5 of Fig. 1, and illustrating the means for controlling and varying the speed of the delivery belts; Fig. 75 6 is a vertical section taken on the line 6—6 of Fig. 1, and illustrating the arrangement and operation of the knife which cuts the web into blanks; Fig. 7 is an elevation and partial section illustrating a means for causing the advance of the web of the fresh supply roll when the roll being used has become exhausted; and Fig. 8 is an end elevation of the parts shown in Fig. 7, and shows certain parts in section on the line 8—8 of Fig. 7.

Referring more particularly to the drawings, at one end of the frame 1 of the machine supply rolls 2 and 3 are mounted rotatably in a suitable bracket and held 90 against shifting longitudinally by means of double guide-arms 4. As indicated in Fig. 2, these guide-arms are mounted on a shaft 5 which enable them to be adjusted to suit rolls of different lengths. The roller 3, as 95 illustrated in Fig. 1, is the active supply roll, and the web 6 thereof passes upwardly around a guide pulley 7, from which point it passes horizontally on a table 8. From this point it passes preferably through a 100 special feeding device which may comprise two rolls 9 and 10; beyond this point it passes through a main feeding device which may comprise rolls 11 and 12. The special rolls 9 and 10 are normally ineffective to advance the web, but the rolls 11 and 12 are 105 preferably arranged so that their adjacent surfaces constantly grip one of the webs so

as to advance it. We prefer to pass the web 6 across the edge of a fixed knife 13 as it passes to a delivery device, said delivery device being arranged to pass the blank to the second machine or forming machine. In the preferred form, this delivery device may comprise rollers 15 and 16 with a plurality of endless belts 14 passing around them; and these belts are preferably arranged so that their adjacent runs 17 diverge toward their receiving end for a purpose to appear hereinafter. These belts are preferably formed of rubber or similar material. Between the special rolls 9 and 10 and the main feed rolls 11 and 12, a removable table or shelf 19 may be provided to support the web. The web 20 of the new supply roll passes around suitable guide pulleys 21 and 22 and lies on top of the web 7 and the table 8, and extends into the special feeding device, or between the special feed rolls 9 and 10 so that its end 23 may lie beyond the special feeding device, as at some point on the table 19, falling short of the main feeding device.

It is to be understood that when we employ the rolls 9 and 10 they are preferably normally separated, so that although they may be rotating constantly they do not grip the webs or tend to advance them. In order to enable the rolls 9 and 10 to come into active operation, we prefer to mount the shaft 24 of the roller 9 upon eccentric sleeves or bushings 25, as illustrated most clearly in Figs. 3 and 7. These bushings 25 are preferably connected by a tie-rod 26 so that they move in unison, and one of the bushings is provided with means for rotating it, such as a rigid arm 27 which may be operated when desired by means of a link 27^a connected with a bell crank 28 and operated by lever 29, as illustrated in Fig. 1.

The means for cutting the web into blanks may comprise a rotating knife 30 which is attached to the hub 31 of a bevel gear 32, which is driven continuously when the machine is in operation. From this arrangement the knife 30 moves in a plane at right angles to the path of the web, and at each revolution it passes the knife 13 on its down stroke so as to sever the web at this point. In order to prevent injury from this knife in its upward movement, it passes through a suitable guard 33. It should be understood that the belts 14 are preferably run at a much higher speed than that of the web when it is severed by the knife, and for this reason it is necessary to prevent the belts 14 from pulling the end of the web violently before the blank is severed. In order to accomplish this we prefer to separate the rollers 15 more fully from each other than the rollers 16, so that the receiving ends of the belts 14 form a diverging space or throat 34 in which the end of the web is received.

However, these belts 14 will grip the web yieldingly, and with sufficient force, that when the blank is severed they will advance it quickly to the forming machine.

The feeding devices may be driven in any desired manner. In order to accomplish this the forming machine may be provided with a large gear wheel, a part of which is indicated at 35, meshing with a pinion 36 on a vertical shaft 37 mounted on the frame 1, 75 said vertical shaft being provided with a bevel gear connection 38 for driving a horizontal counter-shaft 39. This shaft 39 extends across to the other side of the frame, where it is provided with a gear 40 which 80 drives a corresponding gear 41 on a second counter-shaft 42. The shaft 42 has a rigid sprocket wheel 43 over which a chain 44 passes upwardly so as to drive a sprocket wheel 45, said sprocket wheel 45 being rigid 85 with the gear wheel 46 located near the feed rolls. By means of an idler 47 the gear wheel 46 drives the gear 48, which is carried rigidly by the shaft of the lower main feed roller 12. This gear wheel 48 meshes with a 90 similar gear wheel 49 rigidly mounted on the shaft of the upper main feed roller 11. The rollers 9 and 10 are preferably driven continuously in unison by means such as meshing gear wheels 50 and 51, the latter of 95 which is driven by an idler 52 which meshes with the aforesaid gear wheel 46. The gear wheels 50 and 51 are constantly in mesh even when the shaft 24 of the roller 9 is raised to its highest possible position, so 100 that these rollers 9 and 10 are constantly rotating although their faces do not normally pinch the web or webs lying between them. When it is desired to drive the feed rolls 11 and 12 at a higher or a lower speed 105 than that which will result from using the gear 46 of the size shown, the gear 46 may be removed and replaced by another gear of a different diameter. When this is accomplished the idler 47 will be replaced by an 110 idler of a different diameter. Any desired arrangement may be made for adjusting the center of the substituted idler such as that illustrated in respect to the gear 52, however, which may consist in arranging the 115 stud 53 of the gear in a slot 54 in the frame 1 and arranged to slide along in the slot so as to adapt the gear 52 to mesh with the driving gear which has been substituted for the gear 46.

In the present embodiment of our invention, the rollers 16 are driven from a horizontal counter-shaft 55 in the lower part of the frame, by means of a belt 56 which passes around pulleys 57 and 58, the latter 125 of which is rigid on the shaft of the lower one of the rollers 16. The shafts of the rollers 16 have gear wheels 59 which mesh together, so that when the lower roller is rotated the upper one rotates in the opposite 130

direction. Preferably the speed of the delivery device is directly controlled by the operation. To accomplish this the counter-shaft 55 is preferably driven by a belt 60 passing over a pulley 61 on the second counter-shaft 42, and in order to provide for changing the speed of driving the roller 16, we prefer to make the pulleys 57 and 61 in the form of cones, as indicated in Fig. 5; 5 and we provide a belt-shifter 62 consisting of a nut or traveler 63 mounted on an adjusting screw 64, which is adapted to be rotated by a crank 65. This nut 63 forms part of a carriage 66 which slides on a guide bar 67 parallel with the shaft 64. This carriage is provided with arms or forks 68 which engage the edges of the belt 60. From this arrangement it will be evident that when the carriage 66 is moved in either 10 direction, it will shift the belt on the cone pulleys and change the relative speed of rotation of the cone pulleys. In this way the speed of the delivery device is accelerated or retarded at will and independently 15 of the speed of the rest of the machine. 20

The bevel gear 32 which drives the knife is driven from a corresponding bevel gear wheel 68 mounted on the shaft of the upper main feed roller 11. The shafts of all the 30 upper rollers, except the shaft 24, are held in boxes 69 which may be adjusted by adjusting screws 70. The box of shaft 24 is preferably fixed.

The general mode of operation of the 35 present embodiment of our invention will now be briefly described.

A web, such as the web 7 from the lower stock roll 3, is continuously advanced through the machine by the main feed 40 rollers 11 and 12, or other main feeding mechanism. While the revolving knife 30 is removed from the web, the web advances across the edge of the fixed knife 13 and advances into the throat 34 between the belts 45 14. At each downward stroke of the knife 30 a blank is severed from the web, and the delivery device comprising any means such as the belts 14, then advances the blank rapidly to the forming machine or other 50 machine to which the feeding machine delivers. The web 20 with its end lying stationary at the point 23 and preferably in contact with the other, or moving web, lies between the rolls 9 and 10, which are normally ineffective to advance the web. When 55 it is desired to start the new web the special feeding device is rendered active. In the present instance, to do this the arm 29 is pulled upwardly into the position in which 60 it is indicated in Fig. 1. This will rotate the eccentric sleeves or bushings 25 and bring the shaft 24 of the roller 9 down sufficiently to enable the roller 9 to pinch both webs; these rollers 9, 10 then coöperate to 65 advance both the webs until the end 23 of

the web 20 passes between the rolls 11 and 12. The lever 29 can then be returned to its normal position. The operation of changing from the exhausted roller to a fresh supply roller will result in forming a few 70 plates of a double thickness of stock, but this fact is immaterial. As soon as the machine has commenced to run with the new supply roll, the exhausted roll is then removed and a new supply roll substituted 75 therefor. The end of the web of this new supply roll is then extended through the special feeding device. In the present embodiment it is passed around its proper guide rollers and along the table 8, until its 80 end lies between the special rolls 9 and 10 as indicated in Fig. 1. The guide pulleys 7 and 22 are arranged so that they guide their corresponding webs along the upper surface of the table 8 as the webs pass between the 85 rolls 9 and 10 of the special feed device, and hence adjacent the table 8 the guide means for the two webs have a common path, that is, the paths of the two webs at this point are the same. This arrangement greatly 90 facilitates the positioning of the loose end of the web of a fresh roll which is to be substituted for an exhausted roll. If the roll which is becoming exhausted is the roll 3, then the loose end from the roll 2 can be 95 drawn around the pulleys 21 and 22 and laid upon the upper side of the web which is then running through the machine. The moving web from the roll 3 will then carry the loose end of the new roll forward sufficiently to bring it into a position such as 100 that illustrated in Fig. 3, and in which it will lie between the rollers 9 and 10. In a similar manner the loose end of the lower roll can be brought into position by passing 105 it around the pulley 7 and then passing it between the moving web and the table or plate 8. Its movement across the table 8 and between the rollers 9 and 10 cannot be hindered in any way by the moving web, 110 but may be facilitated by contact with the moving web. In other words, the arrangement described enables a web which is being exhausted to assist in carrying the loose end of the next web into place between the rolls 115 116 of the special feed device.

It should be understood that the delivery device which may include the belts 14, runs at a much higher speed than the web advances, so that the delivery device projects 120 or throws the blank at the forming machine. The operator controls this by moving the handle or crank 65 back and forth which causes a speed change, as by shifting the belt 60 in either direction on the speed 125 cones 57 and 61. The delivery device which includes the members 14 and their coöperating parts, is covered by a separate co-pending application, Serial No. 720,917, filed Sept. 18, 1912. 130

As suggested above, the speed of all the feed rolls may be altered as may be desired by such means as substituting different sized gears for the driving gear 46.

5 Although we have shown the machine as adapted to carry only two supply rolls, it is evident that it may be constructed to carry any number of such rolls that may be desired, and it is immaterial whether the stock 10 supply be mounted directly on the machine. It is also immaterial whether the stock be kept in the form of a roll.

We do not limit ourselves to the form of machine or the devices described or illustrated above, as they simply present only 15 one of the many forms our invention may take.

What we claim as new is:

1. In a machine of the class described, in 20 combination, a special feed device arranged to be normally inactive, feeding mechanism arranged to advance a web of stock through said special feed device, guiding means for guiding a web of stock into said special feed device, a second guiding means for 25 guiding a second web into said special feed device, both said guiding means having a common path for the two webs so that the loose end of one web may lie in contact with

the other web when being advanced into 30 said special feed device, and means for actuating said special feed device to advance both webs simultaneously.

2. In a machine of the class described, in combination, a special feed device arranged to be normally inactive, feeding mechanism arranged to advance a web of stock through 35 said special feed device, said special feed device comprising a pair of rolls normally separated and between which the web of stock passes, a guide table disposed before said special feed device, means for guiding two independent webs across said table and between said rollers whereby one of the webs may draw forwardly the free end of 40 the other web to bring the same into position between said rollers, and means for actuating said rollers to pinch the loose end of 45 the web and advance the same with the moving web.

Signed at Hudson Falls, New York, this 50
11th day of June, 1912.

GEORGE S. WITHAM, Sr.
ISAAC J. WITHAM.
